[57] **CLAIM**

The ornamental design for a flexible safety light strip, as shown and described.

DESCRIPTION

FIG. 1 is a perspective view of the flexible safety light strip of the instant invention in a flexed position.

FIG. 2 is a top plan view of the flexible safety light strip of the instant invention in an extended position.

FIG. 3 is an elevation view of the flexible safety light strip of the instant invention as shown in FIG. 2 but rotated 90°.

FIG. 4 is a bottom plan view of the flexible safety light strip of the instant invention as shown in FIG. 2.

FIG. 5 is an end view of the flexible safety light strip of the instant invention taken from the upper end as shown in FIGS. 2, 3 and 4.

FIG. 6 is the opposite end view of the flexible safety light strip of the instant invention taken from the lower end as shown in FIGS. 2, 3 and 4.
